UNITED STATES PATENT OFFICE.

FRANK A. HUMPHREY, OF WORCESTER, MASSACHUSETTS.

SHARPENING-TOOL.

SPECIFICATION forming part of Letters Patent No. 618,880, dated February 7, 1899.

Application filed February 7, 1898. Serial No. 669,299. (No model.)

To all whom it may concern:

Be it known that I, FRANK A. HUMPHREY, a citizen of the United States, residing at Worcester, in the county of Worcester and 5 State of Massachusetts, have invented a new and useful Sharpening-Tool, of which the following, together with the accompanying drawings, is a specification sufficiently full, clear, and exact to enable persons skilled in the art 10 to which this invention appertains to make and use the same.

The object of my present invention is to provide a novel form of sharpening-tool or slip-stone especially adapted for convenient 15 and efficient service in the sharpening of curved cutters, gouges, and round-nosed tools in great variety, either outside or inside bevels, and capable of effecting its work in an expeditious and satisfactory manner. I attain 20 these objects by a sharpening-tool having the peculiar construction illustrated in the drawings, wherein—

Figure 1 is a perspective view showing the outer face. Fig. 2 is a perspective view of the 25 inner face. Fig. 3 is a perspective side view. Fig. 4 is a longitudinal central section at line ww on Fig. 2. Fig. 5 is a transverse section at line XX , Fig. 1. Fig. 6 is a cross-section of the smaller end at line YY , Fig. 1, corresponding to that of Fig. 5. Figs. 5^a and 5^b 30 show modifications in cross-section that I employ as equivalent within the scope of this invention, and Figs. 6^a and 6^b show cross-sections of the smaller end respectively corresponding to the forms of sections Figs. 5^a and 5^b .

My invention consists in a sharpening-tool or article for the purpose set forth formed from gritty or abrasive material—such as co- 40 rundum, emery, comminuted quartz, whetstone, or other suitable grit substance natural or artificial in its compound—and comprising in character a longitudinally-tapered transversely-crescent-shaped rigid body, as 45 hereinafter specifically explained and as defined in the summary.

Referring to the drawings, A denotes the slip or body, preferably formed solid or of

similar substance throughout its mass and essentially shaped as shown, with a larger end 50 B and a smaller end C, between which the body extends with longitudinally-right-lined semiconical or tapering form with a direct uniform taper, while having a transverse shape or cross-section of substantially crescent shape at any portion or interval of its length, (as denoted by the section view on line XX and YY ,) the outer side presenting a straight conoidally-tapering transversely-convex surface 3 and the inner side presenting a straight conoidally-tapering transversely-concave surface 5. The two edges or side lines a , where the convex and concave surfaces come together, are longitudinally straight, but may be made more or less round- 60 ed, equally or unequally, as illustrated in Figs. 5 and 6, or acute, as at a' in Figs. 5^a and 6^a , or, again, if in any instance desired, one edge may be made thin and angular, as at a^2 , and the other rounded, as at a^4 in Figs. 5^b and 70 6^b . Generally the form shown in Fig. 5 is preferred, one edge being rounded off on a circle somewhat smaller than that of the other edge, thus meeting a greater variety of work.

The rounded edges a taper longitudinally 75 from the larger to the smaller end in substantially the same proportions as the convex and concave surfaces, all of the surfaces being abrasive or working surfaces and longitudinally converging toward a smaller end without material change in the general transverse contour or cross-section shape except in size thereof, which varies at different positions in the length of the convergent faces.

The larger end B is best squared off with 85 its surface substantially perpendicular to the axis of an imaginary cone coinciding with the exterior surface 3, so that it presents a flat surface, on which straight-edged cutters can be sharpened or inward angular forms reached 90 by using its corner 8. The smaller end C may be formed square, as at line m , Fig. 2, or with a flat beveled end, as at line m' or m^2 , Fig. 3, but is best made with a rounded or spherical surface 7 at the extremity, the inner and 95 outer curved surfaces merging into each other

by a rounded terminal apex. In the general proportions of this tool the breadth of the end B is about one-third of the length, and the length may be for ordinary sharpening purposes some six to eight inches, more or less, or as required in any special instance.

Woodworking-gouges as manufactured for the trade are among the general forms regularly made in three styles of curve—viz., the 10 “quick” sweep or curve, the “medium” curve, and the “slight” curve, these being standard tools. It is my purpose, in accord therewith, to make the transverse curvature or crescent cross-section of my improved 15 sharpening-tool in quick, medium, and slight curve degrees of modification to meet the requirements for sharpening such curved cutters.

This improved sharpening-tool can be made 20 of any of the various kinds of stone or grit materials, such as are suitable for abrasive or sharpening purposes, either in the natural or artificially-prepared condition. Preferably they are molded or produced from finely- 25 comminuted corundum, emery, or similar grit and a suitable binding medium in solid form—that is, of uniform kind and consistency throughout the entire body—and are rendered hard and permanent by pressure, vitrifying, 30 or other well-known process similar to that applied in the manufacture of grinding-wheels.

In some instances it is found desirable to 35 slightly increase the concavity of the inner surface 5 toward the smaller end relatively to the convexity of the outer surface 3, so that while the surfaces both form a true conoidal taper the edges a near the smaller end will 40 include a greater number of degrees in the concave arc than at the larger end.

By reason of the peculiar construction of 45 the sharpening-tool as herein shown and described I provide a means or instrument suited to the sharpening of gouges, curved cutters, or other round-nose tools of a great variety of sizes and shapes with the single sharpening tool or slip and for both outside and inside edge bevels. Furthermore, I produce a desirable, convenient, and serviceable 50 instrument that has rapid sharpening capacity on this class of work, since the pecul-

iar shape operates to embrace and contact with the rounded cutter in an advantageous and successful manner.

What I claim as my invention, and desire 55 to secure by Letters Patent, is—

1. A sharpening-tool or slip-stone made of abrasive grit material, and comprising a rigid longitudinally-tapered body presenting outward and inward curved sharpening-surfaces, 60 and formed approximately crescent-shaped in cross-section at any position in its length.

2. A sharpening-tool composed of abrasive grit material, formed with a longitudinally-tapering body that is transversely crescent- 65 shaped in cross-section, and having its respective edges formed of different thickness and curvature.

3. A sharpening-tool of an abrasive nature, having a rigid tapered body formed with an 70 abrading outer face transversely convex, and an abrading inner face transversely concave, said convex and concave faces formed on relatively different transverse curvatures, and longitudinally diminished in radius of curvature to relatively different degrees, toward one end thereof, and affording the conoidal sharpening-faces with relatively increasing concavity of the inner face; for the purpose 75 set forth.

4. A sharpening-tool or slip-stone, composed of grit substance such as described, and formed in a solid longitudinally-tapered body having approximately crescent-shaped cross-section with a straight conoidally-tapering convex outer surface, a straight conoidally-tapering concave inner surface, and tapering rounded edge portions, substantially 85 as set forth.

5. The sharpening-tool having the longitudinally-tapered body formed transversely convex upon one face and transversely concave upon its opposite face, the squared-off large end B, and the smaller end C formed with the spherical or rounded apex 7, substantially 90 as shown and described.

Witness my hand this 4th day of February, 1898.

FRANK A. HUMPHREY.
